UNITED STATES PATENT OFFICE.

WILLIAM H. BECKETT, OF DETOUR, MICHIGAN.

GOVERNOR ATTACHMENT.

SPECIFICATION forming part of Letters Patent No. 738,973, dated September 15, 1903.

Application filed May 26, 1903. Serial No. 158,879. (No model.)

To all whom it may concern:

Be it known that I, WILLIAM H. BECKETT, a citizen of the United States, residing at Detour, in the county of Chippewa and State of Michigan, have invented a new and useful Governor Attachment, of which the following is a specification.

This invention relates to the governors employed in connection with steam-engines and similar machinery, more particularly to the class of such devices operated by an endless belt, and has for its object principally to provide means whereby the governor-valve will be instantly closed in event of the breakage 15 or displacement of the belt.

Another object of the invention is to provide a device of this character which may be attached to any of the various forms of governors manufactured without change in the 20 structure of the governor.

Another object of the invention is to produce a device of this character which may be adjusted to adapt it to the governor and increase or decrease its power to correspond to 25 the resistance of the governor.

Further objects and advantages of the invention will appear in the annexed description and the novel features thereof be specifically pointed out in the claims.

30 The improved device may be attached to any of the various forms of governors operated by an endless belt running over pulleys, and I do not, therefore, wish to be limited in the use of the device to any specific form or 35 construction of governor and reserve the right to such modifications and changes which may be found necessary to so adapt it without departing from the principle of the invention or sacrificing any of its advantages.

40 In the drawings illustrative of the invention, in which corresponding parts are denoted by like designating characters, Figure 1 is an end elevation, and Fig. 2 is a side elevation, partially in section, of a conventional 45 form of governor with the improvement applied. Fig. 3 is a perspective view of the supporting-bracket detached. Fig. 4 represents a side view of an improved form of high-speed governor in ordinary use with the improvement applied, and Fig. 5 is a plan view 50 in section on the line 5 5 of Fig. 4.

In the form of governor illustrated in Figs. 1 and 2 the base or valve casing is indicated at 10, having a column or standard 11, extending therefrom and provided with the 55 usual form of valve 12 and stem 13, extending through the column.

The governor-balls are shown at 14, connected by the system of levers 15 and rotating sleeve 16, between the column and stem, the 60 rotation of the balls controlling the valve in the usual manner.

A transverse shaft 17 is mounted for rotation in bearings 18 on the casing 10 and provided on one end with a drive-pulley 19 and 65 on the other end with a bevel-gear 20, interengaging a similar gear 21 on the rotating sleeve 16.

A drive-belt 22 operates upon the pulley from the engine-shaft or other moving part in 70 the usual manner; but as this portion of the device forms no part of the present invention it is not illustrated.

Extending from the casing 10 is a bracket 23, in the lower portion of which a transverse 75 shaft 24 is mounted for oscillation and provided on one end with a relatively short crank-arm 25 and with a relatively elongated lever-arm 26, extending in the opposite direction from the other end, the latter arm having an idler-pulley 27, mounted for rotation on its free end, running in engagement with the belt 22, as shown. The lever-arm 26 is formed in two sections having overlapping 80 ends and provided with spaced apertures 28 85 in the overlapping portions, through which clamp-bolts 29 are passed, to enable the lever-arm to be lengthened or shortened to correspondingly increase or decrease the leverage, if required. 90

Pivotedly connected, as at 30, to the vertical portion of the bracket is a secondary lever-arm 31, connected at one end by a link 32 to the free end of the crank-arm 25 and with the other end bifurcated and engaging opposite sides of the valve-stem 13 above a stop 33, as shown. 95

When the governor is operating properly, the belt 22 will support the pulley 27 and arm 26 and hold the smaller arm 25 in its downward position, as in full lines in Figs. 1 and 2, and by means of connecting-link 32 the sec- 100

ondary lever 31 will be held in an inoperative position and will not affect the governor or interfere with its action under the influence of the balls 14.

5 In event of the breakage or displacement of the belt 22 the lever-arm 26 and its pulley 27 is immediately transformed into a relatively long and powerful lever, working upon the relatively short arm 25 and connecting link 10 and lever 31 to cause them to throw the valve-stem downward and close the valve 12, and thus shut off the steam and stop the engine. By this means the engine will not "run away" in event of the breakage or displacement of 15 the governor-belt; but the governor will be immediately and automatically "cut out" of action in event of such an accident.

In Figs. 4 and 5 an ordinary high-speed governor is shown, with the governor-balls 20 and valve-stem arranged and operating reversely to the governor, (shown in Figs. 1 and 2,) illustrating the manner in which the improved trip mechanism may be connected to this form of governor. In this connection 25 it will be noted that the bracket 23 is modified somewhat in form to adapt it to the structure of the governor and is secured in place about the base 10 by a clip or strap 34 and nuts 35. In this modification the lever-arm 30 26 and pulley 27 are supported by the belt 22 in the same manner as in Figs. 1 and 2, and thus prevent the arm 36 from operating the bell-crank lever. Then in the event of the 35 breakage or displacement of the belt the dropping of the lever-arm will rotate the shaft 24 and cause the arm 36 to operate the bell-crank lever, and thus move the valve-stem 13 and close the valve in the same manner as heretofore described in connection with the 40 mechanism shown in Figs. 1 and 2.

While I have thus shown two forms of governor-valves in common use, it is obvious that with slight and immaterial modifications in the form of the bracket 23 and the leverage 45 mechanism between the shaft 24 and the valve-stem the device may be readily adapted to any form of governor-valve now in use wherein a driven belt or similar operating mechanism is employed without departing 50 from the principle of the invention or sacrificing any of its advantages.

Having thus described the invention, what I claim is—

1. The combination of a governor-valve

having a stem extending therefrom, governor-balls mounted for rotation and adapted to control the movements of said valve, a drive-pulley connected to impart motion to said balls, a drive-belt operating upon said drive-pulley, a primary lever-arm intermediately pivoted and extending by one end over said belt and supported thereby, a secondary lever-arm intermediately pivoted and movably connected by one end with said valve-stem, and a link connecting the free ends of said 65 lever-arms, whereby the breakage or displacement of the drive-belt will cause the closure of said valve, substantially as described.

2. In a governor, a valve-casing, a valve 70 movably seated in said casing and provided with an extended stem, governor-balls mounted for rotation and connected to control said valve, a drive-shaft connected to operate said governor-balls and provided with a drive-pulley, a drive-belt operatively engaging said drive-pulley, a supporting-bracket connected with said valve-casing, a shaft mounted for oscillation upon said bracket, and having a primary lever-arm extending therefrom in 75 one direction over said drive-belt and supported thereby and provided with a crank-arm extending in the opposite direction, a secondary lever-arm intermediately pivoted to said bracket and movably connected by 80 one end to said valve-stem, and a link connecting the other end of said primary lever-arm to said crank-arm, substantially as described.

3. The combination of a governor-valve having a stem extending therefrom, governor-balls mounted for rotation and adapted to control the movements of said valve, a drive-pulley connected to impart motion to said balls, a drive-belt operating upon said drive-pulley, a lever-arm extending over said belt and supported thereby, means for adjusting said lever-arm to change its length, and means for connecting said lever-arm with said valve-stem, substantially as described.

In testimony that I claim the foregoing as my own I have hereto affixed my signature in the presence of two witnesses.

WILLIAM H. BECKETT.
